(57) **CLAIM**

The ornamental design for a telecommunications device, as shown and described.

DESCRIPTION

FIG. 1 is a front view elevation of a telecommunications device showing my new design;

FIG. 2 is a top and front perspective view thereof; and, FIG. 3 is a rear and side perspective view thereof, the side opposite being substantially a mirror image.

The broken lines shown in FIGS. 1 and 3 are for illustrative purposes only and form no part of the claimed design.
